UNITED STATES PATENT OFFICE.

JOSEPH W. HAYS AND CHARLES W. HAYS, OF CHICAGO, ILLINOIS.

GAS ABSORBING AND INDICATING APPARATUS FOR GAS-ANALYZERS.

1,153,912.

Specification of Letters Patent. Patented Sept. 21, 1915.

Original application filed July 17, 1913, Serial No. 779,547. Divided and this application filed September 14, 1914. Serial No. 861,738.

To all whom it may concern:

Be it known that we, JOSEPH W. HAYS and CHARLES W. HAYS, citizens of the United States, residing in the city of Chicago, county of Cook, and State of Illinois, have invented certain new and useful Improvements in Gas Absorbing and Indicating Apparatus for Gas-Analyzers, of which the following is a specification.

Our invention relates especially to automatic gas analyzers but it may be applied in a practical way to hand manipulated apparatus, as it affords means for a direct reading of the result of the analysis while the gas is in the absorption vessel, thereby materially reducing the time required to make a determination.

We attain the objects of our invention by the means illustrated in the accompanying drawings, in which for the sake of clearness we have shown only those parts of our automatic gas analyzer that relate to the present invention. The fluid leveling device claimed in our copending application, Serial Number 779,547, of which the present application is a division, and the temperature controlling device claimed in our copending application, Serial Number 861,737 are not shown in the drawing. In our copending application; Serial Number 861,736 we show another means for accomplishing the same ends attained by the present invention.

In the drawing, "B" is the burette or gas measuring chamber and "A" the absorption chamber. These are connected by the capillary tube, "CT".

"RB" is a rubber bag immersed in the chemical solution, "PS", with which "A" is charged. The upper part of "A" may be packed with a fibrous material, "SW", if desired, to facilitate the speed of absorption.

"RB" is connected with a tube, "DT" on which there is an indicating scale, "IS". Water, "W" fills the bag, "RB" and partly fills the tube, "DT".

"IT" and "OT" are gas inlet and outlet tubes, leading respectively to and from "B".

"P" is a gas pump, operated by a stream of water delivered through the pipe, "WP". The water is discharged from "P" into the stand-pipe, "StP". The stand-pipe is soldered into the water chamber, "WC" and extends a short distance into same.

"DS" is a discharge siphon which empties the stand-pipe and the water chamber

when the water has accumulated in the stand-pipe to the overflow point, "OF". The tubes, "IT¹" and "IT²", connect with the pipes, "IT" and "OT", as shown, and are soldered into the top of "WC".

"BP" is a by-pass valve, connecting the tubes, "IT" and "OT".

The measurement of the gas sample at atmospheric pressure is accomplished by means of the tube, "MT" and the gas bag, "GB", as hereinafter described. The apparatus is charged with the caustic potash solution, or other chemical used, through the tube, "PoT", which is closed by the plug, "PoP". The chamber, "WC¹" and the by-pass valve, "BP", are partly filled with water, "W¹" and "W²".

The apparatus operates as follows: The gas pump, or aspirator, "P", which is operated by a small stream of water delivered through "WP", creates a partial vacuum in the pipe, "OT". This is communicated to "B" and the pipe, "IT", the latter being connected with the source of gas supply. As a result of the lowered pressure, gas flows through, "IT", "B" and "OT" to "P", where it mingles with the water. The water, "W²", is discharged into "StP" and accumulates in "WC". The water in a few moments reaches and seals the lower end of "StP", whereupon a quantity of air is trapped in "WC". This air is compressed by the static action of the water accumulating in "StP". As a result of this pressure water is displaced from the chamber "WC¹", through the tubes, "IT¹" and "IT²" into the tubes, "IT", "OT" and "MT" and the burette, "B". When the water reaches and seals the lower ends of the tubes "IT" and "OT", the flow of gas is shut off and a quantity of gas is trapped in "B" and "MT". The gas flow is short-circuited through "BP", following the stoppage of flow through "B". As the water rises toward "B" some of the trapped gas is displaced into "MT" and the distensible gas bag, "GB". When "MT" is sealed by the water the exact quantity of gas required is trapped off in "B" and in the tube connecting the upper part of "B" with "IT".

This exact quantity of gas is measured at the pressure of the atmosphere. The water continues to rise and pushes the gas through the capillary tube, "CT" into "A", displacing the liquid chemical, "PS". This displacement puts a pressure upon the rubber

bag, "RB" and water is in turn expelled therefrom into the tube "DT". It is plain to be seen that the height to which the water rises along the scale, "IS", is inversely proportional to the volume of gas absorbed in "A". If it is desired to produce a record of the analysis, a low pressure recording gage may be connected by tube with the tube, "DT". "A" may be packed with a fibrous material, "SW", which we have found greatly expedites the operation of absorption.

It would of course be possible to secure an indication by connecting the tube, "DT," with the lower part of the chamber, "A," dispensing with the rubber bag and the water, "W," but such indication could not be relied upon. It would be necessary to make up a chemical solution of a predetermined specific gravity and the indications would be correct, assuming proper calibration of the scale, "IS," as long as there was no material change in the gravity of the chemical solution. But the specific gravity of the chemical solution would not remain constant. It would change as the gas absorbed would form salts in the solution. It would, therefore, be impractical, for the above and other reasons, to employ the absorber chemical as an indicating fluid. To meet the requirements we have devised the arrangement, herein described and claimed. By this arrangement we are able to confine the chemical in the chamber "A," where it will not be exposed to anything except the gas introduced into "A." It will be necessary in some cases to employ a chemical affected by the oxygen of the air, and if such chemical were displaced into an open tube and used as an indicating fluid it would rapidly deteriorate. The arrangement enables us to employ a liquid, such as water, for an indicating fluid and the specific gravity being constant, no error will result in the indications. The use of the flexible rubber bag renders it possible to transmit pressure from the one liquid to the other without loss.

We claim:

50. 1. A gas analyzer consisting of gas measuring and absorber vessels; a chemical in said absorber vessel; a tube sealed into said absorber vessel and a distensible bag within said vessel attached to said tube.
55. 2. A gas analyzer consisting of connected gas measuring and absorber vessels; a liquid chemical in the absorber vessel; a tube sealed in said absorber vessel; a distensible bag within said vessel attached to said tube and a liquid in said bag and said tube.
60. 3. A gas analyzer consisting of connected gas measuring and absorber vessels; a liquid chemical in the absorber vessel; a tube sealed into said absorber vessel; a distensible bag within said absorber vessel attached to said

tube; a liquid in said bag and said tube and means for forcing gas from said measuring vessel into said absorber vessel, displacing said liquid chemical thereby deflating said bag and expelling the liquid therefrom into 70 said tube.

4. A gas analyzer consisting of connected gas measuring and absorber vessels; a liquid chemical in said absorber vessel; a tube sealed into said vessel; a distensible bag 75 within said vessel attached to said tube; a liquid in said bag and said tube; means for forcing gas from said measuring vessel into said absorber vessel thereby displacing said liquid chemical, deflating said bag and displacing said liquid and means for measuring the quantity of liquid so displaced.

5. A gas analyzer consisting of connected gas measuring and gas absorber vessels; a chemical in the absorber vessel; a distensible bag in said absorber vessel; a fluid in said bag; an exterior connection with said bag; means for forcing gas from said measuring vessel into said absorber vessel, deflating said bag and thereby applying pressure to 90 the fluid in said bag, and means for measuring the pressure applied to said fluid.

6. A gas analyzer consisting of connected gas measuring and absorber vessels; a liquid chemical in the absorber vessel; means for forcing gas from said measuring vessel into the absorber vessel, displacing said liquid chemical, and means for taking up the displacement of said liquid chemical.

7. A gas analyzer consisting of connected gas measuring and gas absorber vessels; a liquid chemical in said absorber vessel; means for forcing gas from said measuring vessel into said absorber vessel, and a compressible body in said vessel to take up said 100 displacement.

8. A gas analyzer consisting of connected gas measuring and gas absorber vessels; a chemical in the absorber vessel; a tube sealed into said absorber vessel; a distensible bag within said vessel, attached to said tube; a liquid in said bag and said tube; pressure means for transferring gas from said measuring vessel to said absorber vessel, displacing the liquid in said bag and said tube, and means for restoring the liquid in said tube to predetermined normal level.

9. An absorbing and indicating apparatus for a gas analyzer consisting of a closed vessel connected with a gas measuring means; a distensible chamber located in said vessel and connected with an exterior registering device.

10. An absorbing and indicating apparatus for a gas analyzer consisting of a closed vessel having a compressible chamber located therein.

11. An absorbing and indicating apparatus for a gas analyzer consisting of a closed vessel having a compressible chamber lo-

cated therein and means for registering or indicating the compression of said chamber.

12. A gas analyzer consisting of a gas measuring means, a gas absorber means and a pressure indicating means, the latter consisting of a compressible chamber actuating an indicating device.

13. A gas analyzer consisting of connected gas measuring and absorber vessels, two liquids of different character in said ab-

sorber vessel and a separating medium between said liquids.

In witness whereof we have hereunto set our hands and seals this 17th day of August, 1914.
